REFINING OF NITRILES

John W. Teter and Walter J. Merwin, Chicago, Ill.,
assignors to Sinclair Refining Company, New
York, N. Y., a corporation of Maine

No Drawing. Application October 6, 1943,
Serial No. 505,196

3 Claims. (Cl. 202—42)

1

This invention relates to the refining of nitriles and relates more particularly to an improved method of separating hydrocarbon impurities from nitriles of three to four carbon atoms per molecule, i. e. propionitrile and butyronitriles.

These nitriles may with advantage be prepared by the amination of olefinic hydrocarbon at an elevated temperature. The crude, stabilized nitrile product of such amination is usually composed primarily of a mixture of propionitrile, iso-butyronitrile, and normal butyronitrile and frequently contains hydrocarbon impurities. These nitriles may be isolated by close fractional distillation of the crude product. However, the thus isolated nitriles are frequently contaminated by hydrocarbons which distill off within the same temperature range as the nitrile and which pass over with the respective nitriles from the fractionating operation in varying amounts, as an azeotrope.

The complete separation of such hydrocarbon impurities from these nitriles by direct fractional distillation has heretofore been extremely difficult, if not impossible.

Our present invention provides a method whereby substantial complete removal of these hydrocarbon impurities from these nitriles may be effected by direct fractional distillation.

We have discovered that the hydrocarbon contaminant of the nitrile fractions forms an azeotrope with acetonitrile in the presence of the other respective nitriles, which azeotrope has a boiling point substantially below that of these other nitriles and may be separated therefrom by fractional distillation without substantial loss of the other nitriles.

The boiling point of pure propionitrile, for example, is approximately 97° C. and that of pure acetonitrile is 82° C. The azeotrope formed by acetonitrile and the hydrocarbon contaminants has been found to boil slightly below 82° C., at atmospheric pressure.

Further, the acetonitrile has been found not to form binary azeotropes with any material quantity of either of the other nitriles previously noted herein, or ternary azeotropes with these nitriles and the hydrocarbon impurities, to any substantial extent. A small amount of propionitrile may be carried over with the acetonitrile but this amount is so small as to have little effect on the efficiency of the operation even if not subsequently recovered. Thus substantially complete removal of the added acetonitrile and the hydro-

2

carbon impurity from the other nitriles noted may be readily effected by distillation.

Utilizing this peculiarity of acetonitrile and the hydrocarbon contaminant to form a readily separable azeotrope in the presence of propionitrile and butyronitriles, the processing of our present invention comprises adding acetonitrile to the nitrile-hydrocarbon mixture and fractionally distilling the mixture to separate the acetonitrile-hydrocarbon azeotrope from the other nitriles. The optimum proportion of acetonitrile to be added will depend primarily upon the proportion of the hydrocarbon contaminant present.

15 Most of the hydrocarbon readily separates from the acetonitrile constituent of the azeotrope fraction as an upper layer upon cooling the fraction to room temperature and more may be removed by chilling. The lower acetonitrile layer will contain most, if not all, of any propionitrile carried over with the azeotrope fraction and may be recycled with the decanted acetonitrile to the nitrile purification tower. The upper hydrocarbon layer will usually contain about 1.5% of dissolved acetonitrile, at room temperature. This acetonitrile may be recovered by water washing, dried and returned to the nitrile purification tower.

The invention has also been found to be applicable to the direct purification of a stabilized mixed nitrile product resulting, for instance, from the catalytic amination of propylene. This product, as previously noted, usually contains various nitriles along with hydrocarbon impurities and sometimes contains small amounts of acetonitrile. In accordance with this aspect of my invention the hydrocarbon impurities may be removed directly from the nitrile mixture prior to isolation of the respective nitriles. Usually the amount of acetonitrile present, if any, is insufficient to carry off completely the hydrocarbon impurities. Accordingly it is usually necessary to add to the mixture acetonitrile from an extraneous source. However, we have found that the proportion of acetonitrile in the stabilized product can be regulated somewhat by the choice of the catalyst used and other operating conditions of the amination process. By this application of my invention the hydrocarbon impurities are distilled from the mixture with the acetonitrile and thereafter propionitrile and the butyronitriles substantially free from hydrocarbon impurities may be directly obtained.

Our present invention contemplates either batch or continuous operation. In either type of

operation, the acetonitrile layer of the azeotrope fraction is with advantage recycled to the nitrile purification zone to carry off further hydrocarbons. In this way the acetonitrile requirement is considerably reduced. Intermediate fractions may also be recycled for further purification.

In small scale operation, particularly, we have found it frequently desirable to add, in addition to the acetonitrile, a portion of a stable higher boiling liquid to constitute a residual liquid in the still, which will not be decomposed or distilled off at the distillation temperature of the nitriles or of the azeotrope and which will not interfere with separation of the acetonitrile-hydrocarbon azeotrope from the mixture. We have found capronitrile, for instance, to be satisfactory for this purpose. By its use, danger of polymerizing and coking of the nitrile being distilled is substantially avoided and a more complete recovery of the nitrile is made possible. However, it will be understood that the use of such extraneous bottoms material is not essential to our purification process.

The invention will be illustrated by the following specific examples:

Example I

A synthetic mixture was prepared from 20 cc. of pure propionitrile, having a refractive index of 1.3662 at 20° C., and 2.8 cc. of hydrocarbons separated from hydrocarbon-contaminated propionitrile by chilling it. To this mixture there was added 50 cc. of acetonitrile and the entire mixture was subjected to fractional distillation in a 9.5 millimeter Stedman column. The acetonitrile-hydrocarbon fraction distilled off at a substantially constant temperature beginning at 78° C. and finally rising to about 81° C., indicating exhaustion of the hydrocarbon contaminant. The propionitrile fraction distilled off at about 96° C. and was found to be substantially free from hydrocarbon impurities as indicated by a nitrogen content of 24.6% and a refractive index of 1.366 at 20° C., which is substantially that of the propionitrile used in the preparation of the synthetic mixture.

Example II

4160 cc. of a normal butyronitrile product, contaminated with hydrocarbons and having a refractive index at 20° C. of 1.3850 and a nitrogen content of 19.3%, was subjected to fractional distillation in a two inch Stedman column with an equal volume of acetonitrile. In this distillation, 1930 cc. of capronitrile also was added to act as an extraneous bottoms. The acetonitrile-hydrocarbon fraction distilled off at a temperature of 80 to 81° C., the temperature finally rising gradually to 82° C. for a brief period indicating exhaustion of the hydrocarbon impurity from the mixture. Thereafter the temperature rose sharply to 114° C. and then gradually to 118° C. In this last mentioned temperature range over 40% of the charge, excluding the extraneous bottoms, was obtained and this fraction was found to contain approximately 20% nitrogen and to have a refractive index of 20° C. of 1.3840, indicating it to be substantially pure normal butyronitrile.

Example III

1390 cc. of an iso-butyronitrile product, contaminated with hydrocarbon and having a refractive index at 20° C. of 1.3737 and containing 19.9% nitrogen, was subjected to fractional distillation in an one inch Stedman column with

an equal volume of acetonitrile, no extraneous bottoms being added. The acetonitrile-hydrocarbon fraction came off at a temperature of 80.5-81° C., the temperature remaining substantially constant until about 50% of the charge was distilled off and then rapidly rising to 101° C. and finally gradually rising to 102° C. The refractive index of the acetonitrile-hydrocarbon fraction at 20° C. was 1.3462 but toward the end of the cut dropped to 1.3441, approximating that of pure acetonitrile and indicating that the hydrocarbon impurities of the mixture had become exhausted and that more than the required amount of acetonitrile had been added. The nitrogen content of the iso-butyronitrile fraction was 19.3% and its refractive index was 1.3731, substantially that of pure iso-butyronitrile, indicating complete removal of the hydrocarbon impurities therefrom. About 820 cc. of the pure iso-butyronitrile was thus obtained. Its specific gravity was found to be 0.7712.

Example IV

To 100 cc. of a crude stabilized mixed nitrile product, resulted from the direct amination of propylene there, there was added 50 cc. of acetonitrile. The mixture was then subjected to fractional distillation in a 9.5 millimeter Stedman column.

Approximately 44 volume percent of the mixture distilled off at a temperature below 82° C., including 7.5% of material distilling off below 75° C. Between the point where 7.5 to that where 29 volume percent of the charge was distilled off, the distillate separated into two layers upon cooling to room temperature. The refractive index of the upper layer at 20° C. rose from 1.412 to 1.420. Thereafter the distillate no longer separated upon cooling to room temperature and the refractive index of the distillate fraction dropped sharply to 1.351 and finally to 1.3450 at a temperature of 82° C., indicating that the hydrocarbon impurities, originally present in the mixture, had been substantially exhausted and relatively pure acetonitrile was being distilled off.

After about 44 volume per cent had been distilled off the temperature rose sharply to 94° C. and at 94 to 96° C. a fraction was obtained having a refractive index of 1.3655 and a nitrogen content of 24.1%, indicating that it was relatively pure propionitrile. Finally at 116.5° C. a fraction was obtained having a refractive index at 20° C. of 1.3840 and containing 19.4% nitrogen, indicating that it was substantially pure normal butyronitrile. Thus, by our improved process, the respective nitriles, uncontaminated by hydrocarbons may be obtained directly from a crude mixture of the nitriles containing hydrocarbons.

The hydrocarbon contaminant normally present in these nitrile products has been found by analysis to consist of about 12.6% paraffins, 64% olefins, 20.6 naphthenes, and 2.8% aromatics.

The identity and composition of the hydrocarbon contaminants may vary somewhat. However, we have consistently found them to be substantially completely removable from propionitrile or the butyronitriles or mixtures thereof by our improved distillation process.

The invention is specifically illustrated in the foregoing examples by complete fractional distillations of the mixture. It will be understood, however, that the invention also contemplates an operation wherein the distillation proceeds

only to the point where the acetonitrile-hydrocarbon fraction has been distilled off.

We claim:

1. In a process for removing from nitriles of the class consisting of propionitrile, normal butyronitrile, and iso-butyronitrile, hydrocarbon impurities having boiling points such that in mixtures with said nitriles they normally distil in approximately the same temperature range as said nitriles, the improvement which comprises subjecting the hydrocarbon-contaminated nitrile product to fractional distillation in admixture with acetonitrile and distilling off the hydrocarbon-contaminant and acetonitrile as an azeotrope.
2. In a process for removing from nitriles of the class consisting of propionitrile, normal butyronitrile and iso-butyronitrile, hydrocarbon impurities having boiling points such that in mixtures with said nitriles they normally distil in approximately the same temperature range as

said nitriles, the improvement which comprises adding acetonitrile to the hydrocarbon-contaminated nitrile and distilling off the hydrocarbon-contaminant and acetonitrile as an azeotrope.

3. In a process for removing from nitriles of the class consisting of propionitrile, normal butyronitrile and iso-butyronitrile, hydrocarbon impurities having boiling points such that in mixtures with said nitriles they normally distil in approximately the same temperature range as said nitriles, the improvement which comprises subjecting the hydrocarbon-contaminated nitrile product to fractional distillation in admixture with acetonitrile, distilling off a fraction comprising acetonitrile and the hydrocarbon-contaminant, cooling said fraction, whereby the distillate is separated into an upper hydrocarbon layer and a lower acetonitrile layer and returning the lower layer to the zone of fractional distillation.

JOHN W. TETER.
